UNITED STATES PATENT OFFICE.

VIRGIL PRICE, OF WOODSIDE, NEW YORK.

DESIGN FOR SWORD-HILT AND SCABBARD.

Specification forming part of Design No. 6,763, dated July 8, 1873; application filed March 27, 1873.

To all whom it may concern:

Be it known that I, VIRGIL PRICE, of Woodside, in the county of Queens and State of New York, have invented a new and original Design for a Sword-Hilt and Scabbard, of which the following is a specification:

Figure 1 is a side view of my new design for a sword-hilt. Fig. 2 is a side view showing my new design for the upper part of the scabbard. Figs. 3 and 4 are side views, respectively, of my new design for the middle and top ornaments, respectively, of the sword-scabbard. Fig. 5 is a side view on a reduced scale of a sword-hilt and scabbard, containing my new design.

This invention relates to a new ornamentation of sword-hilts and scabbards, more particularly intended for use by the members of the society known as the Independent Order of Odd Fellows. My invention consists, first, in a new design for the knob or upper end of the sword-hilt, the same consisting of the representation of Justice, with sword and scales in hand, but with eyes uncovered and seated on a dolphin. My invention consists, secondly, in a new configuration of the cross-piece at the lower part of the hilt, the said cross-piece containing in the center the representation of a winged hour-glass and scythe, while over the length of the cross-piece a bow with arrows is placed, as shown. Above the winged hour-glass is a band, containing the various-colored jewels which indicate the various degrees of the Knights of Pythias. My invention also consists in a new design for the shield which is suspended from the sword-hilt over the upper part of the scabbard, the said shield

being ornamented by the representation of three female figures, of which one holds a child, the second a book, and the third an anchor, to personify Love, Faith, and Hope, respectively. The moon and stars are shown over these figures and masonic emblems at their sides, all of which is shown in Fig. 1. My invention consists further in a new design for the upper part of the sword-scabbard, the same representing a tent in front of a cedar tree, with a warrior and a pilgrim standing before the tent, as shown in Fig. 2. Finally, my invention consists in a new ornamentation of the scabbard-tip, which is shown in Fig. 4, and which contains the representation of a female head between a pair of wings, and above the same are wings flanked by ram's heads, and ornamented by decorative foliage, as shown.

What is here claimed and desired to be secured by Letters Patent, is—

1. The design for the knob or upper end of the sword-hilt, as shown.
2. The design for the cross-piece and lower part of the sword-hilt, as shown.
3. The design for the shield on the cross-piece of a sword-hilt, as shown.
4. The design for the upper ornament of a sword-scabbard, as shown in Fig. 2.
5. The design for the middle ornament of a sword-scabbard, as shown in Fig. 3.
6. The design for the lower or tip ornament of a sword-scabbard, as shown in Fig. 4.

VIRGIL PRICE.
